UNITED STATES PATENT OFFICE.

AUGUST HERMANN SCHMIDT, OF HAMBURG, GERMANY.

VALVE-GEARING.

SPECIFICATION forming part of Letters Patent No. 687,070, dated November 19, 1901.

Application filed June 14, 1901. Serial No. 64,576. (No model.)

To all whom it may concern:

Be it known that I, AUGUST HERMANN SCHMIDT, a subject of the German Emperor, and a resident of Hamburg, in the German Empire, have invented certain new and useful Improvements in Valve-Gearings, of which the following is a specification.

The present invention relates to improvements in distributing valve-gearing for quick-running pumps, and has for its object to produce such a valve-gearing which is exceedingly simple in construction and thoroughly efficient and reliable in operation.

The invention consists in several features of construction, as hereinafter described and claimed with reference to the accompanying drawing, in which I have shown a longitudinal sectional elevation of my improved distributing valve-gearing in connection with a pump.

The characteristic feature of my new valve-gearing consists in the arrangement of the compressing-springs n' n^2 and m' m^2 above and below the suction and forcing or delivery valves s and g , respectively. These springs are alternately compressed and released by the rods h' and h^2 , the latter being actuated both in the same and in the opposite direction of the motion of the pump-piston (plunger) by means of the eccentrics t' and t^2 , which are fixed onto the shaft e , whereas the crank c' of the shaft e , running in the bearings l' and l^2 , actuates the pump-piston by means of the connecting-rod d and the piston-rod h , working in the gland a .

According to the foregoing the action and operation of my valve-gearing are as follows: In the drawing I have shown the pump-plunger c at the limit of its forcing stroke, the crank c' , connected with the plunger-rod h through connecting-rod d , being in a position to reverse the stroke of the plunger, the valve-rod h^2 under the action of its eccentric t^2 having completed its downstroke and closed the delivery-valve g by the action of the collar o on the spring m^2 , whereby the latter is compressed and the valve held firmly to its seat. This downstroke of the valve-rod h^2 , and with it its collar o^2 , relieves the spring n^2 of pressure and allows it to expand, said spring moving with the rod out of contact with the hub

of the valve g , in which said rod has free motion. At the same time the valve-rod h' has made its upstroke under the action of its eccentric t' , the collar p' on said rod having moved out of contact with spring m' , while collar p' has moved the spring n' into contact with the hub of the suction-valve s and brought it under sufficient tension to unseat the valve, which takes place as soon as the stroke of the pump-plunger is reversed—that is to say, the moment the pump-plunger c begins its suction-stroke—so that the body of water drawn in through suction-pipe v flows freely or practically without resistance into the pump-chamber. As the pump-plunger c completes its suction-stroke and is about to begin its forcing stroke the valve-rod h^2 will also have completed its upstroke, collar o' moving spring n^2 into contact with the hub of delivery-valve g and placing said spring under sufficient tension to unseat said valve the moment the plunger c begins its upstroke, the water passing freely or with practically no resistance from the pump-chamber to the delivery branch w . At the same time the valve-rod h' has completed its downstroke, its collar p impinging upon spring m' during this movement, compressing the same, and thereby moving the suction-valve s and holding it firmly to its seat, while spring n' is relieved of tension by the movement of the collar p' away from the hub of valve s .

As will be readily understood, the valves g and s are gravity-valves and are held up to 85 and moved off their seats by a tension device on either side of the valve, the tension of which is controlled by the valve-rod, so that said tension device is brought gradually under tension or relieved of tension practically 90 in proportion to the reduction of pressure on the valve. Thus, for instance, the springs m^2 n' , acting on valves g and s , gradually move the same to and from their seats, this being the case in respect of the springs n^2 and m' , except that the valve g is unseated and valve s is seated and whereby the hammering of the valves is practically avoided.

To secure reliable and steady motion of quick-running pumps, the following well-known condition must be fulfilled: The head or forcing valve must have been closed at the

commencement of the sucking period or must, at least, be closed so quickly that a partial receding of the water from the outlet or forcing pipe into the pump-casing is impossible. 5 This rapid closing of the forcing-valve must take place without any jars whatever. The sucking-valve must be sufficiently relieved at the commencement of the forcing period to allow the water to enter without or nearly 10 without any resistance. The sucking-valve must have been closed at the commencement of the forcing period or must be closed without any jars in due time to prevent the water in the pump-cylinder from flowing back 15 into the suction-pipe. At the commencement of the forcing period the forcing-valve must be relieved or balanced as much as possible, so that the water can flow from the cylinder of the pump without any hindrance at the 20 commencement of the stroke. The stroke of the valves must always correspond to the speed of the plunger-piston as nearly as possible in order to obviate acceleration or retardation in the flow of the water, as such 25 intermittent flow causes irregular action and jars of the pump. During the reversal from suction to forcing no change in the direction of the flow of water ought to take place.

The above conditions are entirely or practically entirely fulfilled by my improved valve-gearing, as will be evident from the following facts: As soon as the plunger-piston has passed the point of its greatest 30 velocity the spring m^2 of the forcing-valve g is gradually compressed by the influence of the corresponding eccentric t^2 , the result being that the compressed spring m^2 closes the said valve immediately the stroke is reversed, and as at the same time the lower spring n' is com- 35 pressed by the action of the ascending motion of the eccentric t' the sucking-valve becomes relieved, and consequently opens at once automatically on the diminution of pressure in the pump-cylinder. At the com- 40 mencement of the forcing period the sucking-valve is closed so rapidly and without any jars that a backflowing of the water from the pump-cylinder into the suction-pipe cannot take place. Simultaneously the forcing- 45 valve g is relieved so far as to be capable to be raised by the aid of the compressed spring n^2 , thus permitting the water to pass from the cylinder through the outlet w into the forcing-pipe at the beginning of the stroke. The 50 diminution of the valve motion before its entire closing is brought about by the gradually increasing compression of the spring, whereas the increase of the valve motion at the com- 55 mencement of the stroke of the plunger-pis- 60 ton is caused by the increasing body or bulk of the conveyed water. The reversal of the direction of the flow of water is obviated as

far as possible by the descending of the plunger-piston during the sucking period.

Of course I can apply the herein-described 65 means not only to single-acting but also to double-acting pumps.

It is also understood that I can employ expansion-springs in the place of compression-springs to cause the desired motion of the 70 valves, said expansion-springs being expanded according to the desired degree of the valve motion.

Having fully described my invention, what I claim, and desire to secure by Letters Pat- 75 ent, is—

1. The combination with the pump chamber and plunger, the suction and forcing ports of said chamber, gravity-valves controlling said ports, a crank-shaft connected with the 80 plunger and eccentrics on said shaft; of a tension device on either side of each of and arranged to act directly on said valves and means controlled by the eccentrics on the crank-shaft to cause one or the other of said 85 tension devices to act upon its valve to seat or unseat the same according as the plunger makes its suction or forcing stroke, for the purposes set forth.

2. The combination with the pump chamber and plunger, the suction and forcing ports of said chamber, gravity-valves controlling said ports, a crank-shaft connected with the plunger and eccentrics on said shaft; of valve- 90 rods on which the valves are loosely mounted, 95 said rods connected with the eccentrics and having an abutment on either side of their respective valves, and springs loosely mounted on either side of the valves between them and the abutments on their respective rods, 100 for the purpose set forth.

3. The combination with the pump chamber and plunger, the suction and forcing ports of said chamber, gravity-valves controlling said ports, a crank-shaft connected with the 105 plunger and eccentrics on said shaft; of valve- 110 rods on which the valves are loosely mounted, said rods connected with the eccentrics and having an abutment on either side of their respective valves, and springs loosely mounted on either side of the valves between them and the abutments on their respective rods, 115 said abutments so arranged that the one on one side of a valve will, during the stroke of the rod, move out of contact with the spring on that side, while the abutment on the opposite side of the valve will on the reverse stroke of the rod move its spring out of contact with the valve, substantially as and for the purpose set forth.

AUGUST HERMANN SCHMIDT.
